FRICTION DEVICE FOR FILLING CARRIERS

Sherwood O. Dodge, Medford, Mass., assignor to
Guaranteed Parts, Inc., Allston, Mass., a corporation of Massachusetts

Application April 30, 1934, Serial No. 723,081

8 Claims. (Cl. 139—251)

- This invention relates broadly to a friction device for filling carriers and particularly to a holder by means of which a friction device may be effectively held in a position to yieldingly engage that 5 filling carrier located in a rotary hopper for carriers which is located in transferring position and is next to be transferred to the shuttle.
- The principal object of the invention is to provide a simple effective device for engaging the 10 filling carrier which is located in transferring position and creating sufficient pressure thereon to prevent said carrier from rotating in the hopper as a consequence of a vibration of the latter, to the end that the filling will not unwind from the 15 carrier and be subjected to the danger of breaking during the subsequent operation of the shuttle after the carrier has been transferred thereto.
- Another object of the invention is to provide a holder of novel construction by which the friction member of the device may be guided and 20 adjusted together with a means for simultaneously clamping the friction member to the holder and the holder to a support.
- Another object of the invention is to embody 25 in the device a friction element of a character which will yield upon engagement with the filling to conform slightly to irregularities on the surface of the filling and which will not cause injury to the filling because of its engagement therewith.
- Still another object of the invention is to so 30 construct the friction device that it will also constitute an effective means for aiding and supporting a filling carrier while said carrier is located in transferring position.
- 35 The invention consists in a friction device for filling carriers as set forth in the following specification and particularly as pointed out in the claims thereof.

Referring to the drawing:—

- 40 Fig. 1 represents a vertical sectional elevation of a portion of a filling replenishing loom, including a lay having a shuttle mounted thereon, a hopper for filling carriers, and a transerrer mechanism for said carrier, a friction device for filling 45 carriers embodying my invention being illustrated associated therewith.

Fig. 2 is a plan view partly broken away and 50 illustrated in section of a portion of the mechanism illustrated in Fig. 1 and including the friction device of this invention.

Fig. 3 is a side elevation of the friction device.

Fig. 4 is a detail transverse section taken on the line 4—4 of Fig. 3.

Fig. 5 is a detail plan view of the flexible friction member.

Figs. 6 and 7 are perspective views of modified embodiments of the invention.

Like numerals refer to like parts throughout the several views of the drawing.

In the drawing, referring to Figs. 1 to 4 inclusive, 5 represents a portion of the frame of a filling replenishing loom, 6 a lay, 7 a shuttle box and 8 a shuttle positioned in said box. Mounted upon the frame 5 is a stand 9 for a rotary bobbin disc 10 constituting a portion of a hopper 11 in which 10 a plurality of bobbins 12 constituting filling carriers are mounted in a well-known manner. Mounted on the stand 9 is a fixed transerrer stud 13 upon which is pivotally mounted a transerrer 14 provided with a downwardly projecting arm 15 15 to which a transerrer dog 16 is pivotally attached at 17. The dog 16 is adapted to be engaged by a bunter 18 mounted on the lay 6 to effect the operation of the transerrer 14 in a well-known manner and cause a bobbin 12 which is located 20 in transferring position in the hopper 11 to be forced downwardly from said hopper into the shuttle 8.

All of the parts hereinbefore mentioned are 25 old and their operation is well known in the art. It is also well known that portions of this mechanism, particularly the hopper 11, are caused to vibrate excessively with the result that there is 30 a tendency for the filling carriers 12 to rotate upon the portions of the hopper upon which they are mounted, thereby causing the filling to unwind. When this happens it is a common occurrence after the filling carrier has been transferred to the shuttle for the filling thread to break 35 when the shuttle is driven across the lay with the result that the loom is caused to stop and production therefore is stopped until the loom is again started.

The friction device of this invention is mounted 40 upon an arm 19 which is rigidly fastened to the transerrer stud 13 by a set screw 20. A finger 22 constituting a top holder is rigidly secured in any suitable manner to a pivot member 21 which is 45 mounted to rotate in a bearing provided at the outer extremity of the arm 19. Mounted upon the opposite end portion of the pivot member 21 from that upon which the top holder 22 is mounted 50 is a friction device 23 embodying therein a sleeve 24 which is secured to the pivot member 21 by a cotter pin 25 and said sleeve 24 therefore rotates in unison with said pivot member. The sleeve 24 is recessed at 26 to provide a space for receiving a coil spring 27 surrounding the pivot member 21 and one extremity of said spring is connected to the arm 19 and the other extremity 55

to the sleeve 24 in a manner to cause the top holder 22 to engage a stop provided upon the arm 19 at which time the top holder will be located in a position to support the small end portion of the filling carrier 12 when said carrier is located in transferring position.

Mounted upon and extending around the periphery of the sleeve 24 of the friction device 23 is a holder 28 for a friction member 29. The holder 28 is constructed as a band of sheet material and terminates at its opposite ends in parallel clamping portions 30 and 31. The friction member 29 is adjustably mounted upon the clamping portion 30 of the holder 28 and is secured thereto by means of a guide 33 and bolt 34, the latter passing through the guide 33, through a slot 35 provided in the friction member 29 and through slots provided therefor in the clamping portions 30 and 31 of the holder 28, and said bolt 34 and a nut 36 thereon simultaneously clamp the guide 33 and friction member 29 to the holder 28 and said holder to the sleeve 34. The friction member 29 is constructed of flexible material as, for example, rubber or a material having the characteristics of rubber and is provided with a bevel surface 32 which is adapted to underlie the filling carrier 12 which is located in transferring position and yieldingly engages the filling thereon in a manner to prevent said carrier from rotating in the hopper 11. The friction member 29 will furthermore act as an aid in supporting the carrier 12 with which it contacts. It is desirable that the material of which the friction member 29 is constructed shall be sufficiently flexible to conform slightly to the contour of the surface of the filling with which said member contacts to the end that said member will effectively grip the filling material and thereby prevent the carrier from rotating without injuring the filling.

The friction member 29 is adjustable toward and away from the filling carrier 12 with which it is adapted to contact in order that it may be correctly positioned with respect to said filling carrier. The friction member 29 is positioned upon the holder 28 by means of the guide 33 which is constructed as an inverted U-shaped member, the parallel arms of which engage the opposite edges of the clamping portion 30 of the holder, see Fig. 4, and when the friction member 29 is clamped between the guide member 33 and the portion 30 of the holder by means of the bolt 34 and its nut 36 this clamping action is utilized as a means for also clamping the holder 28 to the sleeve 24.

It will be understood that the arm 19, pivot member 21, top holder 22, sleeve 24 and spring 27 are all old and well known in the art and that the top holder 22 tips downwardly to release the carrier 12 every time a transfer is made. Applicant has utilized the pivot member 21 and sleeve 24 as a support for his improved friction device 23.

In the operation of the loom, as the hopper 11 is rotated to successively position the filling carriers 12 into transferring position, the surface of the filling of the carrier next to be transferred will engage the bevelled surface 32 of the friction member 29 and the latter will yield slightly and engage the filling with a gentle flexing contact which will prevent the carrier from rotating and at the same time not injure the filling during the interval that the carrier is located in transferring position and at the time that the carrier is transferred to the shuttle. When the transfer is made the friction device 23 will rock in unison with the top holder 22 as the latter releases the carrier.

In Fig. 6 I have illustrated a modified embodiment of my invention in which 37 comprises a holder having parallel clamping portions 38 and 39 embodied therein between which a friction member 40 is positioned and this friction member is clamped securely between the portions 38 and 39 of the holder 37 and the latter is clamped securely to a sleeve 24 by means of a bolt 41 and nut 42. It is evident that the friction member 40 may be adjusted between the clamping portions 38 and 39 by moving said member 40 inwardly or outwardly as may be desired.

In Fig. 7 still another modified embodiment of the invention is illustrated in which 43 comprises the holder having parallel clamping portions 44 and 45 embodied therein between which a friction member 46 is secured. The holder 43 is securely clamped to a sleeve 24 by means of a bolt 47 and nut 48. In securing this device to the sleeve to which it is attached there will be a clamping action to compress the friction member 46 between the portions 44 and 45, but this action will not be as effective as in the other embodiments of the invention previously described.

In all the embodiments of the invention the friction members will be constructed of a flexible material which will not injure the filling when contacting therewith.

I claim:

1. A friction device for the filling carriers of a filling replenishing loom comprising, in combination, a support, a sleeve rotatably mounted thereon, a holder upon said sleeve, a friction member mounted upon said holder and adapted to engage the filling on a filling carrier next to be transferred from a hopper for a reserve supply of filling carriers to a shuttle located therebeneath, and means to clamp said friction member to said holder and the holder to said sleeve.

2. A friction device for the filling carriers of a filling replenishing loom comprising, in combination, a support, a sleeve rotatably mounted thereon, a holder upon said sleeve, a flexible friction member mounted upon said holder and adapted to yieldingly engage the filling on a filling carrier next to be transferred from a hopper for a reserve supply of filling carriers to a shuttle located therebeneath, and means to clamp said friction member to said holder and the holder to said sleeve, whereby the friction member may tip downwardly in contact with the filling on a carrier during the transferring operation.

3. A friction device for the filling carriers of a filling replenishing loom comprising, in combination, a support, a sleeve rotatably mounted thereon, a holder upon said sleeve, a friction member mounted upon said holder and adapted to engage the filling on a filling carrier next to be transferred from a hopper for a reserve supply of filling carriers to a shuttle located therebeneath, means to guide said friction member upon the holder, and means to simultaneously clamp said guiding means and friction member to the holder and the holder to said sleeve.

4. A friction device for the filling carriers of a filling replenishing loom comprising, in combination, a support, a sleeve rotatably mounted thereon, a holder comprising a band surrounding said sleeve, a friction member mounted upon said band and adapted to yieldingly engage the filling on a filling carrier next to be transferred from a hopper for a reserve supply of filling carriers to a shuttle located therebeneath, and means to simultaneously clamp said friction member to said band and the band to said sleeve.

5. A friction device for the filling carriers of a filling replenishing loom comprising, in combination, a support, a sleeve rotatably mounted thereon, a holder comprising a band surrounding said sleeve, a flexible friction member adjustably mounted upon said holder and adapted to yieldingly engage the filling on a filling carrier next to be transferred from a hopper for a reserve supply of filling carriers to a shuttle located therebeneath, and means to clamp said friction member to said holder and the holder to said sleeve, whereby the friction member may tip downwardly in contact with the filling on a carrier during the transferring operation.
- 10 6. A friction device for the filling carriers of a filling replenishing loom comprising, in combination, a support, a sleeve rotatably mounted thereon, a holder comprising a band surrounding said sleeve, a flexible friction member adjustably mounted upon said holder and adapted to yieldingly engage the filling on a filling carrier next to be transferred from a hopper for a reserve supply of filling carriers to a shuttle located therebeneath, a guide upon said holder and engaging the edges of said friction member, and means to simultaneously clamp said guide and 10 friction member to said holder and the holder to said sleeve.
- 15 7. A friction device for the filling carriers of a filling replenishing loom comprising, in combination, a support, a sleeve rotatably mounted thereon, a holder comprising a band surrounding said sleeve and embodying therein parallel clamping portions, a flexible friction member mounted between said clamping portions and adapted to yieldingly engage the filling on a filling carrier 20 next to be transferred from a hopper for a reserve supply of filling carriers to a shuttle located therebeneath, and means to simultaneously clamp said friction member between said clamping portions, and said band to said sleeve, whereby the 25 relative position of both holder and friction member may be adjusted simultaneously with respect to the filling carrier.

SHERWOOD O. DODGE.
